CARL WESSEL, OF BORBECK, NEAR ESSEN-ON-THE-RUHR, GERMANY, ASSIGNOR TO THE
FIRM: CARL STILL, OF RECKLINGHAUSEN, WESTPHALIA, GERMANY

COKE OVEN AND THE LIKE

Application filed July 6, 1926, Serial No. 120,731, and in Germany July 17, 1925.

My invention relates to coke ovens or the like of the well-known chamber type defined laterally by heating walls and below by a base for supporting the charge in which the volatile products of distillation developed in the charge in the chamber are withdrawn downwards through the base of the chamber.

According to the invention, exchangeable frames comprising bars arranged like a furnace grate are inserted in vertical openings or passages provided in the base of the oven chamber, through which the volatile products of distillation can flow to a lower horizontal channel preferably extending along the length of the chamber.

This arrangement ensures an efficient withdrawal of the gases and vapors generated without the passages being blocked, and enables an undisturbed discharge of the finished coke.

A further object of the invention is to provide parts serving the said purpose which can be readily removed and exchanged when worn by use.

A still further object is to prevent any liquid condensates arising in the coal charge from finding their way into the passages and blocking them by the incrustations formed.

An example of a construction according to the invention is shown in the accompanying drawings.

Fig. 1 is a vertical cross section of a horizontal coke oven showing one oven chamber and its two lateral heating walls, together with the bottom portions;

Fig. 2 is a vertical longitudinal section taken on the line 2—2 of Fig. 1, showing the lower part of the oven chamber;

Fig. 3 is a horizontal section and plan view taken on the line 3—3 of Fig. 2.

The chamber *d* of the coke oven shown is laterally defined by heating walls, the vertical flues of which are heated from below by a combustible gas and air in the manner represented in Fig. 1. At the bottom of the oven chamber *d*, a base *s* exists upon which the coal charge rests and the finished coke slides parallel to the heated side walls when being discharged.

In the longitudinal centre line of the base *s* of the oven chamber there is a series of vertical openings or passages *c* through which all volatile products of distillation are led from the chamber into a draw-off channel *k* provided below the chamber. In each of these passages *c* a frame *a* is inserted from above so as to be easily exchangeable. It consists preferably of a box-shaped member which tapers downwards and is provided with bars *r*, arranged like a furnace grate, which bars run parallel to the longitudinal axis of the chamber and therefore also in the direction of the coke discharge and leave between them spaces for the passage of the gases and vapors. The bars *r* are also tapered downwards, so that the free spaces are somewhat wider below than above. The upper common surface of the frame and of the bars lies flush with the surface of the base *s* of the chamber. The frames comprising the bars can be made of metal, for example cast iron, or of a ceramic material, for example well-burnt fire clay.

The construction of the frames *a* prevents their being choked by particles of coal or the like during the working of the oven. If during the charging of the oven chamber, particles of coal find their way into the spaces between the bars *r* and are wedged therein, they will either be cut out during the discharge of the finished coke or forced downwards by the pressure due to the coke sliding over them when the latter is pushed out from the oven chamber. The arrangement of the bars *r* parallel to the longitudinal axis of the chamber and to the direction of discharge of the finished coke considerably lessens the friction and the resistance to sliding during the discharging. Likewise, by arranging the tops of the frames *a* and bars *r* flush with the surface of the base *s*, any disturbance or obstruction of the discharging is obviated. Should a frame *a* in the course of time be worn away too much or perhaps, for example, in consequence of incrustations formed, allow too small a free passage, it can be removed by means of suitable tools from its particular opening *c* and replaced by another, or

cleansed and again inserted. The frames *a* can be removed at places adjacent to the ends of the oven chamber laterally through the door openings, and in the middle portion of the chamber from above through the charging openings in the chamber ceiling.

- 5 The base *s* of the chamber is preferably, as shown in Fig. 1, somewhat raised in the centre and sloped away to each side, in order to prevent any liquid condensates which are formed from the products of distillation flowing into the frames *a* and forming a choking incrustation. In a chamber base constructed as shown, the condensates which 10 eventually arise tend to flow laterally to the hot oven walls and to be evaporated on the hot oven base, with the advantage that the latter is also cooled by the consumption of latent heat of evaporation.
- 15 20 What I claim is:

1. In a horizontal coke oven chamber provided with a gas offtake for said chamber comprising a series of openings or passages arranged in the base thereof and spaced 25 away from the side walls, exchangeable grate frames seated in said openings with the tops of said frames flush with the top surface of the chamber base, the bars of said frames extending in a direction parallel to said chamber, and a channel extending longitudinally of said chamber and communicating with the chamber through said openings for receiving the volatile products of distillation.
- 30 2. In a horizontal coke oven chamber provided with a series of openings or passages arranged in the base thereof and spaced from the side walls, exchangeable grate frames having downwardly tapered sides 35 seated in said openings with the tops of said frames flush with the top surface of the chamber base, the bars of said frame also being downwardly tapered and extending in a direction parallel to said chamber, and a channel extending longitudinally of said chamber and in said base below the chamber 40 for receiving the volatile products of distillation through said grated openings.
- 45 3. In a horizontal coke oven chamber, a base, side walls adjoining the base, said base provided with openings or passages arranged along the central longitudinal line of said chamber and spaced from the side walls, exchangeable grate frames seated in 50 said openings with the tops of said frames flush with the top surface of the chamber base, the bars of said frames extending in a direction parallel to said chamber, and a channel extending longitudinally of said chamber and communicating with the chamber through said openings and for receiving the volatile products of distillation.
- 55 4. In a horizontal coke oven chamber, a base, side walls adjoining the base, said base being provided with a series of openings or

passages arranged along the central longitudinal line of said base and spaced from the said walls, exchangeable grate frames seated in said openings with the tops of said frames flush with the top surface of the chamber base, the bars of said frames extending in a direction parallel to said chamber and the surface of said base sloping downwards on each side from the line of openings toward the side walls, and a channel extending longitudinally of said chamber and communicating with the chamber through said openings for receiving the volatile products of distillation.

5. In a horizontal coke oven chamber, a base, side walls adjoining the base, said base provided with openings or passages arranged therein along the central longitudinal line of said base and spaced from the side walls, grate frames seated in said openings, and a draw-off channel communicating with the chamber through said openings for receiving the volatile products of distillation, said base having a sloping upper surface for preventing liquid condensates from 80 passing into said channel.

In testimony whereof I affix my signature.
CARL WESSEL.
